UNITED STATES PATENT OFFICE.

LAWRENCE T. AYRAULT AND JOHN AYRAULT, JR., OF TONAWANDA, NEW YORK.

FASTENING DEVICE FOR ROOFING FABRICS.

Application filed June 26, 1923. Serial No. 647,846.

To all whom it may concern:

Be it known that we, LAWRENCE T. AYRAULT and JOHN AYRAULT, Jr., citizens of the United States, residing at Tonawanda, in the county of Erie and State of New York, have invented certain new and useful Improvements in Fastening Devices for Roofing Fabrics; and we do hereby declare the following to be a full, clear, and 10 exact description of the invention, such as will enable others skilled in the art to which it appertains to make and use the same.

Our invention relates to devices for securing roofing or siding fabrics, sheets, shingle slabs or the like to roof boards or other fabric supports. It has for its several objects to prevent the siding or roofing fabric from buckling where expansion or contraction occurs, and, in the case of shingles, 15 to obviate curling usually incident to long exposure under atmospheric conditions; also, to effect the exclusion of moisture from beneath the respective layers of the siding or roofing fabric, and to prevent access of 20 moisture to the nails and to the perforations in the fabric caused by the latter in securing the fabric to its support.

Our invention involves the following principal features of construction: First; 25 an elongated transversely curved or cupped body member having burs on its convex surface, with or without projecting or offset nail tabs, said body member being adapted uninterruptedly to clamp or hug the surface 30 upon which it is superposed and the burs thereof adapted to engage a superposed or overlapping surface, thereby excluding moisture and also counteracting the tendency of the fabric to buckle or to curl at 35 its edges. Second; a rib or ribs adjacent to the nail holes adapted to indent or be embedded in the overlying fabric, thereby excluding moisture from the nails and from the perforations in the fabric caused by the 40 nails which connect the fastening device to the fabric and its support. Third; elongated nail slots in the nail tabs of the fastener adapted to permit efficient placement of the fastener and of the securing nails thereof, 45 whereby cracks, knots and other imperfec-

tions in the support may be avoided in securing the fabric in position.

In the drawings accompanying and forming part of this specification,—

Figure 1 is a plan view of a fastener embodying our invention. 55

Figure 2 is a plan view of portions of several courses of fabric shingles illustrating the application of our fasteners thereto.

Figure 3 is a transverse sectional view of 60 a portion of the applied roofing shown in Fig. 2.

Figure 4 is a transverse sectional view of the fastener, taken on the line 4—4, Fig. 1.

Figure 5 is a view showing the manner of 65 applying our fastener in laying sheet fabric.

In the drawings illustrating a preferred embodiment of the invention, the scope whereof is pointed out in the claims. 1 indicates the elongated body member of our 70 fabric fastening device. Its length may be proportioned to its preferred location or use, whether with sheet fabric, shingles or slabs. The body member 1 is transversely curved or cupped, as at 2, so that its edge 3 75 may be forced down and caused uninterruptedly to engage or indent the underlying surface.

Projecting laterally from the body member 1 are a series of nail tabs 4 perforated 80 for the passage of the nails by which the fastener is secured to the fabric support. For purposes of locating nails so as to avoid knots, cracks, etc., these perforations are preferably elongated as indicated at 5. 85

The body member 1 of the fastener is also provided in or on its convex surface adjacent to its edge 3 with a series of burs or projecting points 6 adapted to enter the under surface of the superposed fabric and 90 be clinched by the blow of a hammer.

The body member 1 is preferably provided on its convex surface, back of and parallel to the line of the burs 6, with a continuous rib 7 adapted to embed itself in the 95 under surface of the superposed fabric; and each nail tab 4 is also ribbed, being preferably provided with a pair of ribs 8 arranged on opposite sides of its nail slot 5. These ribs preferably extend to and connect 100

with the longitudinal rib 7 of the body member 1. In applying the fabric to its support these several ribs 7 and 8 become embedded in the under surface of the fabric, thus excluding moisture from between the layers. While also possessing the well known advantage of stiffening the material of which the fastener may be formed and thus lessening the cost of manufacture by enabling a lighter or thinner material to be used therefor, the thinness of the fastener thereby made practically possible results in the avoidance of ridge formations or ripples on the surface of the laid fabric.

15 Fabric fastening devices of the character hereinbefore set forth may be utilized in applying siding or laying roofing as follows: In laying shingles upon a roof or siding it is preferred to dispose them in courses in the usual manner of laying shingles as indicated at F, G, and H in Fig. 2. Before laying the course F a series of the fastening devices is placed and attached to the roof boards or other support in any suitable manner, but preferably by means of nails passing through the elongated slots 5, which latter permit of the positioning of the nails to secure a firm attachment. The convex burred surface of the fastener is exposed.

20 The shingles of the course F are next applied so that the burs 6 will penetrate the lower edges of the several shingles. The burs may be then clinched by a hammer blow, which also causes the edge 3 of member 1 to hug or indent the underlying support or fabric, as the case may be, and likewise causes the ribs 7 and 8 to sink into or indent the fabric of the immediately overlying course F. Courses G, H, and each succeeding course, may be laid in like manner, a suitable lower portion of each course being left exposed as is ordinarily done in laying shingles. The nails which pass through the courses into the roof boards or other support are covered in turn and protected by the superimposed courses.

25 In laying a fabric sheet or shingle strip, as indicated in Fig. 5 of the drawings, it is preferred to leave a marginal space of from three to six inches for lapping as shown at K. On this margin the fastening devices may be placed and secured with the burs thereof arranged to engage the superposed sheet of the fabric adjacent its edge.

30 Among the advantages of our invention are the effective exclusion of moisture from the under side of the fabric sheets or shingles, thus effectually protecting the fastening nails and the perforations in the fabric through which they pass; the locking or holding of the fabric against working loose around the burs, thus preventing wear and tear and buckling of the fabric; and the clamping action of the curved and ribbed body member which prevents curling and

buckling. The elongated body and short tabs facilitate the straightening of courses after laying, as well as in repair work; and the ribbed body of light material results in the avoidance of wave or ripple formations in the laid shingles or shingle courses. It is practical by use of our fastener, which prevents curling or buckling of the applied fabric, to lay large as well as small shingles of a light weight fabric, thus rendering unnecessary the use of heavier multiple layer fabric such as is now required. This results in a material saving in the manufacture and application of siding and roofing fabrics.

35 We claim:—

1. Fastening means for roofing and siding fabrics comprising a body member adapted to be interposed between overlapped layers of the said fabric, said body member being transversely arched and having burrs which project upwardly from its convex surface and provide means adapted for securing said body member to an overlying layer of the fabric, and means for securing said arched body member to an underlying fabric support.

2. Fastening means for roofing and siding fabrics, comprising a transversely curved body member provided on its convex surface with a longitudinally disposed rib, and having means for securing a fabric to said body member, and means for securing the fastener to a support.

3. A fastener for roofing and siding fabrics, comprising an elongated transversely curved body member provided with nail tabs and having a longitudinally disposed rib on its convex surface.

4. A fastener for roofing and siding fabrics having a body member provided with a series of spaced burs adjacent to one edge therof and having a rib disposed back of said series of burs.

5. A fastener for roofing and siding fabrics having a body member provided with a nail tab projecting laterally therefrom and having a series of burrs, said body member having on its burred surface a rib extending behind said burrs.

6. A fastener for roofing and siding fabrics comprising an elongated body member having perforated nail tabs, and ribs arranged with relation to the perforations of the nail tabs so as to exclude moisture therefrom.

7. A fastener for roofing and siding fabrics, said fastener having an elongated transversely curved body member provided with a series of burs adjacent to one edge thereof, a rib on the convex face of said body member, said rib being back of the burs and being parallel thereto, and nail tabs having elongated nail slots.

8. Fastening means for roofing and siding

fabrics comprising an elongated body member provided with a longitudinally extending rib and having means for attaching a fabric to said body member, and means for attaching said body member to a support.

9. A fastening device for roofing and siding fabrics, comprising an elongated transversely curved body member adapted to be interposed between overlapped layers of the said fabric, said body member having associated therewith upwardly projecting means

adapted to secure the overlying layer of the fabric in position, and means for attaching said body member to an underlying fabric support, said curved body member when secured to said support serving to engage and clamp an underlying layer of the fabric.

15 In testimony whereof we affix our signatures.

LAWRENCE T. AYRAULT.
JOHN AYRAULT, JR.
